[57] CLAIM

The ornamental design for a skateboard wheel, as shown and described.

DESCRIPTION

FIG. 1 is a front isometric view of the skateboard wheel, showing our new design;

FIG. 2 is a front elevational view thereof;

FIG. 3 is a right side elevational view of the skateboard wheel showing my new design;

FIG. 4 is a left side elevational view of my new design;

FIG. 5 is a top plan view of the skateboard wheel showing my new design;

FIG. 6 is a bottom plan view of my new design; and,

FIG. 7 is a rear elevational view thereof.
